(57) **CLAIM**

The ornamental design for a sidecutter, as shown.

DESCRIPTION

FIG. 1 is an isometric view of a left side embodiment of the sidecutter.

FIG. 2 is another isometric view of the left side embodiment of FIG. 1.

FIG. 3 is a view of the inside face of the left side embodiment of FIG. 1.

FIG. 4 is a front view of the left side embodiment of FIG. 1, taken from viewing plane 4—4 in FIG. 3.

FIG. 5 is a rear view of the left side embodiment of FIG. 1, taken from viewing plane 5—5 in FIG. 3.

FIG. 6 is a top view of the left side embodiment of FIG. 1, taken from viewing plane 6—6 in FIG. 3.

FIG. 7 is another top view of the left side embodiment of FIG. 1, taken from viewing plane 7—7 in FIG. 3.

FIG. 8 is a view of the outside face of the left side embodiment of FIG. 1.

FIG. 9 is a bottom view of the left side embodiment of FIG. 1, taken from viewing plane 9—9 of FIG. 8.

FIG. 10 is an isometric view of a right side embodiment of the sidecutter.

FIG. 11 is another isometric view of the right side embodiment of FIG. 10.

FIG. 12 is a view of the inside face of the right side embodiment of FIG. 10.

FIG. 13 is a front view of the right side embodiment of FIG. 10, taken from viewing plane 13—13 in FIG. 12.

FIG. 14 is a rear view of the right side embodiment of FIG. 10, taken from viewing plane 14—14 in FIG. 12.

FIG. 15 is a bottom view of the right side embodiment of FIG. 10, taken from viewing plane 15—15 in FIG. 12.

FIG. 16 is a view of the outside face of the right side embodiment of FIG. 10.

FIG. 17 is a top view of the right side embodiment of FIG. 10, taken from viewing plane 17—17 in FIG. 16; and,

FIG. 18 is another top view of the right side embodiment of FIG. 10, taken from viewing plane 18—18 of FIG. 16.
